SELECTIVE FUEL TANK CONTENT INDICATOR

Filed July 30, 1943

UNITED STATES PATENT OFFICE

2,356,200

SELECTIVE FUEL TANK CONTENT INDICATOR

Earl L. Bedard, Minneapolis, Minn., assignor to
Minneapolis-Honeywell Regulator Company,
Minneapolis, Minn., a corporation of Delaware

Application July 30, 1943, Serial No. 496,841

5 Claims. (Cl. 73—290)

My present invention relates to a selective indicator for a plurality of tanks, such as the fuel tanks of an airplane engine or the like.

One object of the invention is to provide an indicator which normally indicates the content of a fuel tank from which fuel is being fed to the engine, the indicator being manually connectible with any of the other fuel tanks to determine their contents, as desired, and upon release automatically returning to indicate the tank from which fuel is being used.

A further object is to provide an indicator which will insure the pilot that none other than the tank he is operating on will indicate on the instrument panel, except when he desires to determine the contents of any other selected one of his plurality of fuel tanks.

Still a further object is to provide a single instrument panel indicator for the contents of several fuel tanks, so connected with a selector valve that normally only the tank from which fuel is being used through the selector valve will be indicated on the panel, as determined by the position of the selector valve.

Another object is to provide an electric indicating means for the contents of several fuel tanks wherein two selector switches are so interconnected with each other that one of them may automatically respond to the position of a selector valve and the other may be manually adjusted to determine the contents of any desired fuel tank other than the one being used from, the manual selector switch always returning to position for automatic indication again in response to the selector valve when the manual selector switch is released.

With these and other objects in view, my invention consists in the construction, arrangement and combination of the various parts of my device, whereby the objects contemplated are attained, as hereinafter more fully set forth, pointed out in my claims, and illustrated in the accompanying drawing, wherein:

The figure is a diagram showing a plurality of fuel tanks and a selector valve to which my fuel tank content indicating means has been applied, the electric circuit of the indicating means being also shown diagrammatically.

On the accompanying drawing, I have used the reference characters T^1 , T^2 , T^3 and T^4 to indicate four tanks such as the fuel tanks of an airplane. A selector valve SV is shown having a housing 10 and a rotor 12 . The rotor 12 has a center port 14 and a side port 16 for connection with a fuel supply conduit 18 and an intake con-

duit C^1 respectively. The conduit 18 extends to any source of consumption such as the carburetor or fuel injector of an airplane engine, and the intake conduit C^1 extends to the tank T^1 . The valve body 10 has other intake conduits C^2 , C^3 and C^4 connected to the respective fuel tanks T^2 , T^3 and T^4 .

The selector valve SV is standard equipment on many airplanes and usually includes a control shaft 20 for the rotor 12 and a manually operable control handle 22 . The control handle 22 has a pointer 24 cooperating with indicia such as 1, 2, 3, 4 and "Off" on a dial 26 mounted on the instrument panel, so that the pilot knows which fuel tank is in use at any time and the handle 22 permits him to change to any desired tank. In some instances, means is provided for automatically rotating the shaft 20 from one tank to the next when the fuel supply in the first tank fails.

My selective fuel tank content indicator includes a single gauge G for indicating the contents in any of the tanks T^1 , T^2 , T^3 or T^4 . For the purpose of actuating the gauge G , each tank is provided with a float F operating a potentiometer 28 , and the potentiometers are connected in the circuit of the gauge G and a pair of selector switches. One of these selector switches may be termed a selector valve switch SS , and the other a manual selector switch MS .

The selector valve switch SS has a switch blade 30 and a plurality of contacts 32 , 34 , 36 and 38 . The manual selector switch has a switch blade 40 and a plurality of contacts $30a$, $32a$, $34a$, $36a$ and $38a$. The switch blade 30 is connected with the contact $30a$ and the four contacts of the switch SS are connected with the remaining four contacts of the switch MS , the contact 32 to the contact $32a$, and so on.

A source of current supply such as a generator or a storage battery of an airplane is indicated at 42 . One side of the battery is grounded at 44 and the other side is connected through a dropping resistor 46 to the gauge G and to one side of each potentiometer 28 . The other side of each potentiometer 28 is grounded, as indicated at 48 . The gauge G is also connected to the switch blade 40 and the contacts 32 to 38 are connected to the arms F^1 , F^2 , F^3 and F^4 of the floats F in the respective tanks T^1 , T^2 , T^3 and T^4 . The arms of the floats, it will be noted, variably contact with the resistance elements of the potentiometers and thereby the current flow in the coils of the gauge G , so as to give a reading on the gauge in accordance with the level of the liquid. The gauge,

of course, may be graduated in gallons or the like, as may be desired. This gauge is of the ammeter type and the circuit arrangement may be varied in many ways to give a reading on the gauge in accordance with the liquid level.

The manual selector switch MS may further include an operating shaft 50 for the switch blade 40, a control knob 52 and a dial 54. The switch blade 40 is normally held against a stop 56 which limits its position to engagement with the contact 30a as by a spring 58. By way of example, the spring 58 may be wrapped around the shaft 50 and have its opposite ends engaging an edge of the blade 40 and a stationary pin 60. The dial 54 may be provided with indicia, such as "Auto," 1, 2, 3 and 4, the four numbers indicating the four tanks T¹, T², T³ and T⁴, respectively.

Practical operation

Assuming that the selector valve SV is in position for supplying fuel from the tank T¹ to the supply conduit 18, the selector valve switch blade 30 will be on the contact 32. Accordingly, current flow through the gauge G can be traced through the switch blade 40 of the switch MS, the contact 30a, the switch blade 30, and the contact 32, from which it flows to the float arm F¹. Therefore, the float F in the tank T¹ is the controlling factor for actuating the indicator or gauge G.

When it is desired to determine the contents in any of the other three tanks, the pointer of the knob 52 may be swung to the positions 2, 3 or 4 on the dial 54 and after the gauge reading is noted, the pointer may be swung to any of the other numbers, or the knob 52 released, whereupon the spring 58 will bring the switch blade 40 back to the contact 30a for connecting the circuit with the switch blade 30. Assuming for instance, that the contents of tank T³ is desired to be known, the pointer of the knob 52 may be registered with the indicia 3 on the dial 54 and the circuit from the gauge G then passes through the switch blade 40 and the contact 36a. From the contact 36a, the circuit may be traced upwardly to the float arm F³ so that the potentiometer 28 of the tank T³ is then the controlling factor for the gauge G.

Whenever the knob 52 is released, it will automatically be returned by the spring 58 to the contact 30a, so that the position of the selector valve switch blade 30 is then the controlling factor for the gauge G, regardless of what position the blade 30 may be in. As a result, release of the manual selector switch MS always insures that the subsequent reading on the gauge G is for the tank from which fuel is being used, since the position of the selector valve determines the position of the switch blade 30 and thereby automatically, the proper potentiometer 28 for controlling the gauge G.

In this manner, it is impossible for the pilot to erroneously leave the manual selector switch MS on a tank from which fuel is not being used, thereby permitting him to use fuel from some other tank while the gauge remains at a position indicating fuel in such tank, not being used. If such were the case, fuel from the other tank may be completely depleted, thereby permitting the engine to stop while in flight. This, of course, is a dangerous situation and one that is guarded against by my arrangement.

When the selector valve SV is adjusted to any position other than position 1 as shown, for in-

stance position 3, the switch blade 30 will engage the contact 34 thereby automatically connecting the gauge G with the float arm F³ to indicate the fuel level in the tank T³ from which fuel is then being used. The circuit is then traceable from the gauge through the elements 40, 30, 34, F³ and 28 of T³. The knob 52 may now be registered with any of the indicia 1, 3 or 4 on the dial 54 for momentarily determining the contents of the tanks T¹, T² or T³ and when the spring 58 returns it to position "Auto," the gauge G will give a reading for the tank T³ being used.

Basically, my arrangement makes it impossible for the gas gauge to indicate the contents of a tank to which the engines are not connected, except when the pilot manually moves a switch to any other tank position, such switch being biased to return to an automatic position positively indicating the tank from which fuel is actually being used.

Some changes may be made in the construction and arrangement of the parts of my device without departing from the real spirit and purpose of my invention, and it is my intention to cover by my claims any modified forms of structure or use of mechanical equivalents, which may be reasonably included within their scope without departing from the real spirit and purpose thereof.

30 I claim as my invention:

1. In combination with a plurality of fuel tanks and a selector valve for controlling fuel therefrom to a supply conduit, selective indicator means for the contents of said fuel tanks comprising a single indicating means for all of said tanks, switch means for selecting the tank effective to actuate said indicator means comprising a selector valve switch connected for simultaneous adjustment with said selector valve, a manual selector switch operable to connect said indicator means with any of said tanks desired independent of said selector valve switch, and means to normally return said manual selector switch to a position for permitting said selector valve switch to function.

2. In a selective tank content indicator, the combination with a plurality of tanks, and a selector valve between said tanks and a supply conduit, of content responsive means for each of said tanks, an indicator adapted to be actuated by any one of said content responsive means, a manual selector means for selecting at will the content responsive means to actuate said indicator, and an automatic means responsive to the position of said selector valve for automatically selecting the content responsive means which actuates said indicator in accordance with the position of said selector valve, said manual selector means predominating said automatic means except when it is not being used to determine the contents of a tank other than the one connected to said supply through said selector valve.

3. In combination with a plurality of tanks and a selector valve for controlling fluid therefrom to a supply conduit, selective indicator means for the contents of said tanks comprising an electrically energized content responsive means for each of said tanks, a single electrically actuated indicating means for said tanks, switch means for selecting the content responsive means effective to actuate said indicator means comprising a selector valve switch normally connecting said indicator means with the content responsive means of the tank

from which fuel is being received through said selector valve, a manual selector switch operable to connect said indicator means with the content responsive means of any of said tanks desired, independent of said selector valve switch, and means to return said manual selector switch to a position permitting said selector valve switch to function when the manual selector switch is released.

4. In combination with a plurality of liquid containing tanks and a selector means for controlling the flow of liquid from said tanks to a common conduit, a liquid level indicator, liquid level responsive means for each of said tanks, and means for operatively connecting said liquid level responsive means with said indicator comprising a pair of selector devices, one automatically operable by said selector means as it changes position and the other manually operable, said manually operable selector device having an initial position rendering said automatic selector device operable and other positions rendering it inoperative, said manually operable selector device selectively connecting said indicator with any one of said tanks.

5. In combination with a plurality of fuel tanks and a selector valve for controlling fuel therefrom to a supply conduit, selective indicator means for the contents of said tanks comprising an electrically energized content responsive means for each of said tanks, a single electrically actuated indicating means for said tanks, switch means for selecting the content responsive means effective to actuate said indicator means comprising a multiple point selector valve switch, and a multiple point manual selector switch, said selector valve switch being operable to connect said indicator means with any of said tanks depending on the point of the switch in the indicator circuit, said manual selector switch being operable in normal position to connect said selector valve switch in said circuit and in other positions to disconnect it from said circuit, said manual selector switch, in said other positions, connecting various of said points of said selector valve switch in said circuit independent of said selector valve switch.

EARL L. BEDARD.
